UNITED STATES PATENT OFFICE

WILLIAM STUEBING, JR., OF CINCINNATI, OHIO, ASSIGNOR TO THE YALE AND TOWNE MANUFACTURING COMPANY, OF STAMFORD, CONNECTICUT, A CORPORATION OF CONNECTICUT

REEL RACK

Application filed July 16, 1929. Serial No. 378,640.

The present invention relates to an improvement in racks or skids for supporting reels of cable, wire, and the like. One object thereof has been to provide a skid upon which a reel may conveniently be loaded and transported by means of a lift truck and which will effectively support such a reel in operative position for winding or unwinding.

One embodiment of my invention is illustrated in the drawings accompanying the present specification and in which:

Figure 1 is an end view with a cable reel in position to be operatively engaged by the skid;

Figure 2, a transverse section on the line 2—2 of Figure 1; and,

Figure 3, a side view illustrating a skid with its parts adjusted to support a cable reel in position for winding or unwinding.

Referring to the drawings, a preferred form of my improved skid includes a substantially U-shaped frame having opposed spaced horizontal members 1 and a transverse connecting member 2. An upright 3 is mounted on each of said opposed horizontal members 1 and carries a rack 4. An adjustable bracket 5 is slidably mounted on each upright 3 and is adapted to be retained in any desired position thereon by means of a pawl 6 which is held normally in operative engagement with the rack 4 by means of a counterweight in the form of an arm 7.

In operation, the above described frame and associated parts are positioned with the spaced members 1 straddling a reel or the like which is provided with an axle 8 having its free ends extending across or above the path of movement of the slidable brackets 5. The latter are then moved upwardly into axle engaging position where they are held secure by means of the pawls 6 engaging the racks 4. If now a suitably designed lifting truck be positioned in lifting relation to the frame, the frame together with the cable reel can be raised out of contact with the ground or floor.

The frame of my improved skid is preferably supported in such a manner that the effective height thereof above the ground or

floor may be varied, the purpose being to provide means whereby the reel may readily be maintained in elevated or winding and unwinding position after the lift truck has been removed from beneath the frame. Accordingly, I provide three legs 9, one under an end portion of each of the spaced members 1 and the third located under a middle portion of transverse member 2. Each leg 9 is provided with suitable means for increasing or reducing its effective length, such for example as a spacer 10 pivotally secured thereto and in such position that it may readily be deflected downwardly into a position underlying said leg, as shown in Figure 3, when the frame is in elevated position or, if desired, it may be moved to inoperative position as indicated in Figure 1. By releasing the elevating mechanism of the lift truck the frame is again lowered and comes to rest on legs 9, but, with the spacers 10 in operative position, the reel will stand clear of the ground or floor and can therefore be freely rotated for the purpose of winding or unwinding cable or the like.

It will be apparent from the foregoing description of my improved skid and the statement of its mode of operation that it presents features which are materially advantageous over cable reel handling devices now in use or commonly known before my invention. For example, where a cable reel is supported on an axle between wheels, the latter being of greater diameter than the reel, occupy an unnecessarily large amount of space when the reel is not in use. Furthermore, the difficulties of raising a heavy reel into position to be carried by a pair of wheels makes this method of support and transportation very burdensome and expensive. According to another mode of handling cable reels, the reel is mounted on a support forming part of a transporting device having its own power. The objection to this form of reel carrier is that the very expensive transporting device and the operators thereof must be engaged not only during transportation of the reel but also during the reeling or unreeling of cable. According to my invention, the skid is preferably separable from the truck and

may therefore be deposited at any desired place either for storage or for use, thus relieving the truck for duty elsewhere if desired. Other and possibly equally important advantages in connection with the use of my improved form of reel skid will be apparent upon reading the foregoing specification in connection with the accompanying drawings.

- 10 I claim as my invention:
1. A skid for cable reels and the like comprising a U-shaped frame including spaced horizontal members having inwardly extending flanges adapted to be engaged by and to rest upon the elevating frame of a lift truck or the like, a T-beam upright supported on each horizontal member, a rack on each upright, a reel axle supporting bracket slidably mounted on each upright, and a detent positioned to releasably retain the bracket in any desired position of adjustment in relation to said rack.
  2. A skid for cable reels and the like comprising a U-shaped frame having spaced horizontal members and a transverse connecting member, said horizontal members including opposed inwardly directed extensions having under surfaces adapted to engage and be supported by the elevating frame of a lift truck or the like, supporting means mounted on each horizontal member, a leg for each horizontal member and for said transverse member, and means for varying the length of a plurality of said legs whereby said horizontal members may be supported at different heights from the ground or floor, comprising a foot pivotally secured to each of said plurality of legs and adapted to be moved into and out of leg supporting position when the U-shaped frame is held in raised position on the elevating frame of a lift truck or the like.

In testimony whereof, I have signed my name to this specification this 12th day of July, 1929.

WILLIAM STUEBING, Jr.
